DESIGN FOR A FLUORESCENT LAMP FIXTURE

Henry Dreyfuss, New York, N. Y., assignor to Hy-grade Sylvania Corporation, Salem, Mass., a corporation of Massachusetts

Application June 22, 1940, Serial No. 93,195

Term of patent 7 years

To all whom it may concern:

Be it known that I, Henry Dreyfuss, a citizen of the United States, residing at New York, in the county of New York and State of New York, have invented a new, original, and ornamental Design for a Fluorescent Lamp Fixture, of which the following is a specification, reference being had to the accompanying drawing forming part thereof.

The figure is a perspective view of a fluorescent lamp fixture showing my new design. The tubular cross-bars are the lamps.

I claim:

The ornamental design for a fluorescent lamp fixture, as shown and described.

HENRY DREYFUSS.
